UNITED STATES PATENT OFFICE.

JOHN S. WORTH, OF COATESVILLE, PENNSYLVANIA, ASSIGNEE TO WORTH BROTHERS CORPORATION, OF CLAYMONT, DELAWARE, A CORPORATION OF DELAWARE.

ROLLING-MILL.

1,373,850.

Specification of Letters Patent. Patented Apr. 5, 1921.

Application filed August 27, 1919. Serial No. 320,120.

To all whom it may concern:

Be it known that I, JOHN S. WORTH, a citizen of the United States, and a resident of Coatesville, county of Chester, State of Pennsylvania, have invented certain Improvements in Rolling-Mills, of which the following is a specification.

My invention relates to certain improvements in rolling mills, particularly of the type known as a 5-high mill, in which there are two supporting rolls, one above and the other below the working rolls, and an intermediate roll arranged to be shifted to and from either of the working rolls.

In this type of mill, the working rolls can be comparatively small, yet of an extreme length, as they are supported by the supporting rolls, which are of large diameter, consequently, this rolling mill can be used for rolling the heaviest plates, as well as comparatively thin plates, without the liability of the rolls unduly springing.

In this type of mill the working rolls are positively driven, while the supporting rolls are usually driven by friction from their working rolls. In some instances, the friction of the bearings overcomes the friction of the working rolls, due to the weight of the supporting rolls, so that the supporting rolls remain stationary, or are only partially driven. This is liable to make a defect in the rolls, as the surface speed of the two rolls should be the same.

One object of my invention is to provide means for holding the supporting rolls in a central position between the housings.

Another object of the invention is to provide means for properly hanging the carriers for the upper working and supporting rolls and to provide means for operating the intermediate roll.

Still another object of the invention is to provide means for bodily removing the two working rolls and the intermediate roll, with their carriers, from either end of the machine.

The invention also relates to certain details, which will be fully described herein-after.

While I have described my invention as applied to five-high rolling mills, in which the two working rolls are driven, the invention may be applied to a mill in which the two supporting rolls are driven, or in which

the two supporting rolls and the intermediate roll are driven, as illustrated in the patent granted to me on the 28th day of November, 1916 No. 1,206,637.

In the accompanying drawings:

Figure 1 is a front elevation of a 5-high rolling mill embodying my improvements;

Fig. 2 is an end view;

Fig. 3 is a sectional elevation on the line 3—3, Fig. 1;

Fig. 4 is an enlarged end view illustrating more in detail the bearings of the upper working roll and its supporting roll;

Fig. 5 is a sectional view on the line 5—5, Fig. 4;

Fig. 6 is a sectional elevation on the line 6—6, Fig. 4;

Fig. 7 is a sectional plan view on the line 7—7, Fig. 4;

Fig. 8 is an enlarged end view, showing the bearings for the lower working roll and the intermediate roll;

Fig. 9 is a sectional plan view on the line 9—9, Fig. 8;

Fig. 10 is a sectional view on the line 10—10, Fig. 8;

Fig. 18 is a detached, sectional perspective view of the rest bars of the lower working roll;

Figs. 19 and 20 are sectional views illustrating the spring suspension for the hooks, which carry the cradle of the upper working roll; and

Fig. 21 is a view illustrating a modification of the spring centering arrangement for the rolls.

1, 1 are the housings of the rolling mill,

which are mounted on suitable foundations in the ordinary manner. 2 is the lower working roll. 3 is the upper working roll. 4 is the intermediate working roll, which 5 is mounted so that it can be raised and lowered as in an ordinary 3-high mill. 5 is the lower supporting roll and 6 is the upper supporting roll. The lower working roll 2 is driven from a shaft 7 and the upper working roll 3 is driven from a shaft 8 in the present instance. The two shafts are coupled to their respective rolls by flexible couplings in the ordinary manner. The intermediate roll is not driven in the present instance except by a plate passing between it, and either of the two working rolls, while the lower supporting roll is driven by friction from the lower working roll and the upper supporting roll is driven by friction 20 from the upper working roll.

9 are boxes for the lower working roll. 10 are boxes for the lower supporting roll. 11 are boxes for the upper working roll and 12 are boxes for the supporting roll. 13 are the 25 boxes for the intermediate roll 4. 14 are the adjusting screws located in the upper portion of the housings. These screws can be raised and lowered by the ordinary power mechanism 15 through the gearing shown in 30 Figs. 1 and 2, and from a motor 16 supported on the frame 17 on the upper portion of the housings. The detail construction of the mechanism for turning the screws may be modified without departing from the essential 35 features of the invention.

I will first describe the detail construction of the bearings for the lower supporting roll, whereby a certain portion of the weight is transferred onto a hydraulically 40 operated carrying device through a reduced portion of the spindle.

It will be noted upon referring to Figs. 12, 13, 14 and 15, that the bearings 10 of the lower supporting roll 5 receive the trunnions 18 of the roll. The trunnions must be 45 of considerable size in order to support the roll 5 properly and its working roll while the bloom, or plate, is being rolled.

Under ordinary conditions, this difference 50 in diameter would cause the supporting roll to turn in its bearings when the working roll is turned, but owing to the excessive weight of these rolls, which were heretofore carried solely by the bearings, the supporting roll 55 would in some instances remain stationary when its working roll was rotating, thereby making a defect in the surface of the supporting roll. To overcome this and to insure the positive operation of the lower supporting roll by its working roll, I form a reduced trunnion 19 beyond each trunnion 18 of the roll 5 and these trunnions are mounted in bearings 20 each having a socket 20^a to receive the rounded end 21^a of a plunger 21 65 adapted to a hydraulic cylinder 22. This

cylinder is pivoted at 23 to a frame 24, in the present instance, but can be held rigidly in position by bolts 25, if desired. By this construction the roll is free to be centered by the centering device described hereafter. Each 70 cylinder has the ordinary packing 26 and the lower portion is connected to any suitable water supply under pressure, and is so arranged that when the roller 5 is to be driven by its working roll, the pistons 21 are 75 elevated sufficiently to relieve the bearings 10 of all or any desired amount of pressure of the large trunnions 18, so that instead of the supporting roll 5 being carried by the bearings 10 when the material is not being 80 rolled, it is carried by the bearings 20 through the reduced trunnions 19 so that the difference in diameter between the roll and its reduced trunnions 19 is such that the friction of the trunnions 19 in their bearings 85 20 will not overcome the driving friction of the working roll. The movement is so slight that the trunnions 18 are still fitted to their bearings 10 but the trunnions are relieved from considerable of the dead weight of the 90 two rolls. The cylinders 21 and their plungers 22 are also used to elevate the roll 5 when it is desired to remove it from the mill.

It will be noticed that the roll 5 is slightly less in length than the distance between the 95 bearings 10 and the housings, as illustrated in Fig. 13. In order to hold this roll in the central position and yet to allow it to move to a limited extent longitudinally, I provide a spring device shown clearly in Figs. 12 and 100 13. Secured to the bearings 20 are two rods 27, which are attached to a cross-head 28. In the present instance, each rod is threaded, and nuts 27^a on either side of the cross head, allow for the adjustment of the cross-head in 105 respect to the bearings 20. This cross-head extends through a transverse slot 29 in a frame 30 carried by a U-shaped beam 31 supported on the bed plates 32, which carry the main housings 1.

33 are plungers in the frame 30 having flanges fitting in cylindrical openings 34 closed by caps 35 and between the caps and these flanges are heavy springs 36, which press upon the plungers 33 and as the cross 115 head 28 is located between these plungers, the tendency is to hold the cross head in the central position. In the event of the roll moving longitudinally in its bearings while a plate is in the mill, the springs will immediately return it to its central position as soon as the plate is out, so that the roll is normally held in the central position.

In order to properly support the cylinder 22, I provide two beams 24, mentioned above, 125 in which are the bearings for the trunnions 23 of the cylinders. These beams extend under the main housings, as well as under the U-shaped beam 31. The inner ends of the beams are attached to the main housings 1 130

by bolts 37 and are suspended from the U-shaped beam 31 by brackets 38. This makes a very substantial structure and one which can be readily dismantled in case repairs are necessary to the cylinder, or its parts.

It will be noticed that the cylinders 22 are on each end of the rolling mill, but the centering device is only at one end. While the beams 24 are supported by the U-shaped beam 31 at one end of the mill, the beams 24 at the opposite end are not only supported by the bolts 37, but also by bolts 39 attached to any of the fixed structures of the mill.

15 Referring now to Figs. 1, 3, 4, 5 and 6, the upper supporting roll 6 has trunnions 40, which are mounted in the bearings 12 in the main housings 1, and there are reduced trunnions 41 adapted to bearings 42 mounted 20 in depending portions 43 of a beam 44, which extends from one end of the mill to the other and through the two housings 1, as clearly shown in Fig. 1.

In order to insure the positive turning of 25 the supporting roll 6 with its working roll 3, the trunnions 40 are relieved entirely of their under bearings, and the bearing is taken by the trunnions 41 of small diameter; these also support this roll in case of removal of the working roll 3. On the end 30 of the trunnions 41 is a coupling 45. 46 is a coupling block having projections adapted to the recesses in the coupling 45 so that it will positively turn with it. This coupling 35 block has a frictional surface bearing against a cap 47, back of which is a plunger 48 in a frame 49, which is carried by rods 50, secured to projections on the depending portion 43, as clearly shown in Fig. 5. The 40 plunger 48 has a flange 51 located within a cylindrical opening 52 in the frame 49. Between this flange and a cap 53 is a spring 54. In this instance, there are two of these 45 spring structures, one at each end of the rolling mill, as clearly shown in Fig. 1, so that the tendency of the spring is to hold the upper supporting roll 6 in a central position, yet when the roll moves in either direction while a plate is in the rolls, the 50 springs will have a limited amount of movement, but will always return the roll to the central position when the plate is out. By securing the coupling 45 on the end of the trunnion 41 of the roll 6, when it is desired 55 to drive the roll, a driven coupling can be connected to it after the frames 49 are detached. This may be done in case of repairs, where it is necessary to resurface this roll or for other reasons.

60 While I have illustrated spring-centering means at each end of the upper supporting roll, a spring construction may be located at one end only, so that the upper supporting roll can be positively driven, as well as the 65 lower supporting roll, when necessary.

The transverse beam 44 is carried by two straps 55, which are hung from cross-heads 57 by rods 56. These cross heads are held by plungers 58 adapted to cylinders 59 on the upper structure of the mill on the cross 70 frame 60, which extends from one housing to the other.

These cylinders are hydraulic cylinders and are connected to the ordinary hydraulic mechanism so that the plungers can be raised 75 and lowered, as desired. Consequently, the beam, with its upper supporting roll and upper working roll, can be raised and lowered in the housing. The upper working roll 3 is suspended from the beam 44 by a series of 80 hooked rods 61, which engage the cradle 62 in which the roll 3 is mounted. The upper ends of the rods pass through the boxes 63, in which are located springs 64 so that the upper working roll is yieldingly held 85 against its supporting roll 6. The springs are confined to their boxes by the plate 63^a held by bolts 64^a so that the hooked rods can be readily adjusted without interfering with the tension of the springs— 90 see Figs. 19 and 20. The upper working roll 3 has an extension 65 on which is a disk 66 provided with extended hubs, as shown in Fig. 6. This disk is held to the extension 65 by nuts 67. The disk is mounted 95 in a cage 68 having trunnions 69 adapted to cross-heads 70, as clearly shown in Figs. 6 and 7. The two cross-heads are connected together, as illustrated in Fig. 4, and are mounted between flanged plungers 71 projecting from boxes 72 in which are springs 73, tending to force the plungers out, the plungers being limited by their flanges as clearly shown in Fig. 7. This arrangement is at one end only of the upper working 100 roll 3 and tends to hold the working roll in the central position. The cross-heads 70 are suspended by rods 74 and between a collar on these rods and the frame 75 to which the boxes 72 are secured, is a spring 76, so that 110 these cross-heads are yieldingly supported, insuring the proper centering of the disk 66 in its cage.

77 are washers located between the sides of the disk 66 and its cage. 78 is an annular 115 lining surrounding the disk within the cage. The washers and the lining may be of any suitable anti-friction material. In the present instance, the centering device is only at one end of the roll 3. The other end is 120 grooved to receive a coupling box 79 which connects the shaft 8 with the trunnion of the roll 4—see Fig. 1.

The cradle 62 of the upper working roll has two side members 81, 83, which have 125 ribs 82 extending to a point near the roll above the center of the roll 3 and the upper surface of this extension is inclined and a loose plank, or plate, 83, rests on the portion 82 and bears upon the roll. Water is sup- 130

plied through pipe 84 so that the space above the planks is in the form of a trough for holding water in order to keep the surface of the rolls cool; the plank prevents the water dripping onto a plate while being rolled.

The lower working roll has a construction similar to the upper working roll for holding the roll in a central position. This construction is illustrated clearly in Figs. 1 and 8, in which 70^a are cross heads adapted to the space between the cylindrical boxes 72^a. Instead of these boxes being supported by the beam 44, as is the upper roll, they are supported by brackets 85 projecting from one of the housings 1. They are held flexibly in the space between the boxes by a lever 86 pivoted to a rod 87 attached to the bracket 85. This lever is connected to a link 88 which engages the cross heads 70^a and a rod 89 is connected to the lever 86 between its pivot and the link and extends through the bracket 85. Between a collar on this rod and the bracket 85 is a coiled spring 90. The tension of this spring can be adjusted by nuts 91 so as to hold the cross head 70^a yieldingly in a central position. Otherwise, the construction is similar to that for centering the upper working roll 3. 92 is the cradle which carries the lower working roll. This cradle is suitably mounted in housings 1 and is recessed to receive the heels of the guides 93, which bear upon the roll and the guides 95, made in sections. Between the bearing 9 of the lower working roll and the bearing 10 of the lower supporting roll are spring plates 96 so that the cradle of the working roll is yieldingly carried by this chuck, and the neck of the working roll is relieved of so much friction. The intermediate roll 4 is mounted in a cradle 97, Figs. 3, 8, 9, 10 and 17. This cradle consists of side members 98 in which are recesses 99 to which water is supplied through pipes 100. The two longitudinal bars 98 have extensions 101, which pass through bearings 13 for the trunnions 102 of the intermediate roll 4, and are carried at their outer ends by a cross bar 103, which is suspended by rods 104 from arms 105 on rock shafts 106 adapted to bearings 107 projecting from the housings 1. The rods 104 are adjustable, as shown in Fig. 2. On the shafts 106 are arms 108 to which are attached long links, 109, which are connected to the cross head 110. This cross head, as shown in Fig. 3, has three plungers attached to it, a central plunger 111 and side plungers 112. These plungers are located in a cylinder casing 113 in which are separate cylinders to which water is supplied, the middle cylinder in the present instance, with constant pressure for balancing the roll, and the other two with intermittent

pressure for raising and lowering the roll, or the middle cylinder can be used for operating the roll and the other cylinders for balancing if desired.

In order to attach the bars 98 of the cradle to their respective boxes 13, I perforate the extensions 101 at 114 and locate in these perforations two blocks 115 separated by a wedge 116. These blocks bear against a plate 117 which, in turn bears against the outside of the box 13, so that on adjusting the wedges 116 these bars can be firmly secured to the boxes. The bars 92 of the cradle of the lower working roll, Fig. 11, have extensions 118, which are forked. These extensions pass on each side of the central rib 9^a of the box 9. Bearing against the outside of the box 9 is a plate 119, which is attached to the extension 118 by stud bolts 120 so that on adjusting the nuts on these bolts the bars can be firmly held to the boxes. The bars 62 of the cradle of the upper working roll are held in the same manner to their boxes as the bars of the cradle of the lower working roll and need not be described in detail.

It will be seen by the above construction, that a mill of the 5-high, or 4-high type, in which the upper and lower rolls of the series are the supporting rolls, can be accurately made and the rolls can be properly carried so that the supporting rolls will positively turn with the working rolls, and in which the several rolls will be automatically centered. It has been found in practice that if a roll be slightly out of line, it has a tendency, when in the act of rolling, to move toward one housing or the other. In some instances, this has caused considerable damage, as there was no means of returning the roll to its central position, consequently when the next pass was made, the roll would tend to move longitudinally and would either strain or break the housing or the supporting bearings.

By my invention the rolls are immediately returned to their central position. In 5-high and 4-high rolls, where one is a supporting roll, the tendency for one or both of the rolls to creep is accentuated, but by my arrangement the lateral creeping is allowed, while rolling, but the rolls always return to their central position before another pass is made.

Rolling mills of this type must necessarily have extremely heavy trunnions to support the weight and pressure, consequently, the trunnions are comparatively large in diameter in comparison to the rolls so that the friction of the trunnions in their bearings is sufficient to overcome the friction of the working roll against the supporting roll and, consequently, the supporting roll would cease to rotate and this would wear

a mark in the roll which would have to be removed before the work could proceed, if it was of any great extent.

By providing a journal considerably less 5 in diameter than the main journal of the roll and supporting the dead weight of this roll on this small journal without disturbing the fit of the main journal in the main bearing, the roll will be positively driven 10 by its working roll. The same is the case with the upper roll, which is suspended from the overhead structure.

The cradles of the two working rolls and the intermediate roll with their guides are 15 attached to the bearings of the respective rolls and on the removal of the plate 121 at the side of the housings the entire cradle and its roll can be removed from the end of the housing as one unit, so that the roll, 20 after being trued, can be accurately fitted to its bearings and guides on the outside of the mill, prior to its being inserted in position, and while duplicates thus prepared are being used, saving thereby much delay in 25 operation of the mill.

The plates 122 hold the bearing blocks to the boxes, as clearly shown in Fig. 5. When it is desired to remove the upper supporting roll, it is lowered and then removed 30 through the housings, and the lower supporting roll is raised by the plungers, 21 and then removed through the housings.

Though I have illustrated a different 35 form of spring arrangement for centering the upper supporting roll than that shown in connection with the lower supporting roll, a similar spring construction may be used on the upper supporting roll as on the lower supporting roll.

40 In Fig. 21, I have shown a modification of this spring mechanism in which a single spring 36^a is used with two plungers 33^a and 33^b and a single cross head, one plunger being at one end of the spring and the other 45 at the opposite end of the spring, one plunger bearing directly upon the cross head, while the other plunger is connected thereto through a rod which passes through both plungers.

50 Though I have illustrated cylinders for carrying the lower supporting roll on its small trunnions and also for suspending the upper supporting roll, springs, or levers, may be substituted, if found more desirable 55 in some instances.

My invention while particularly adapted 56 for five-high rolls can be used on four-high, or even on three or two-high rolls, if found desirable.

60 By carrying the upper supporting roll on reduced trunnions and also carrying the upper working roll on hooked bars, I can so adjust these parts that considerable weight will be taken off of the bearings for the up-

per working roll, preventing heating of the 65 bearings, as the parts can be so regulated that just enough pressure can be exerted to cause the supporting roll to be turned on its working roll.

A mill of this type is a universal mill in 70 the sense that very thin and wide plates can be rolled to an accurate gage, as well as the heaviest plates. It is essential that the parts be so made that there will be practically no material defect in the plates when rolled. 75

I claim:

1. The combination in a rolling mill, of working rolls; housings therefor; and automatic means whereby the rolls are centered after the material has passed between the 80 rolls.

2. The combination in a rolling mill, of two working rolls and an intermediate roll; and automatic means whereby the working rolls are centered after each pass of the ma- 85 terial between the rolls.

3. The combination in a rolling mill, of upper and lower supporting rolls; upper and lower working rolls; an intermediate roll; means for driving the working rolls; 90 means for raising and lowering the intermediate roll; and automatic means whereby the working rolls are centered after the material has passed between the rolls.

4. The combination in a 5-high rolling 95 mill, of upper and lower supporting rolls; upper and lower working rolls; an intermediate roll; and automatic means whereby the supporting rolls are centered after the work has passed between the working rolls. 100

5. The combination in a 5-high rolling mill, of upper and lower supporting rolls; upper and lower working rolls; an intermediate roll; and automatic means whereby the upper and lower supporting rolls and 105 the upper and lower working rolls are centered after the material has passed between the working rolls.

6. The combination in a rolling mill, of a working roll; means for driving said roll; 110 a supporting roll under the working roll; bearings, and trunnions on the supporting roll adapted to the bearings; trunnions of less diameter projecting beyond the main trunnions; bearings for the reduced trunnions; 115 and means for carrying these bearings so as to relieve the main bearings from the entire weight of the roll in order that the supporting roll may turn with the working roll.

7. The combination of a working roll and 120 a supporting roll; means for driving the working roll; bearings for the working roll; main bearings for the supporting roll; hous- 125 ings in which the bearings are mounted, the supporting roll having reduced trunnions; bearings carrying the reduced trunnions; and means for lifting the latter bearings so that the weight of the supporting roll will

- be transferred from the main bearings to the bearings of smaller diameter to insure the turning of the supporting roll by the working roll.
8. The combination in a 5-high mill, of 50 housings; bearings for the several rolls mounted in the housings; two supporting rolls; two working rolls and an intermediate roll; means for driving the working rolls, 55 each of the supporting rolls having reduced trunnions; bearings therefor; and means for carrying the said bearings so that the weight is transferred from the main bearings to the auxiliary bearings, insuring turning of the 60 supporting rolls by the working rolls.
9. The combination in a 5-high rolling mill, of housings; bearings mounted in the 65 housings; upper and lower working rolls; upper and lower supporting rolls; one supporting roll being back of each working roll; an intermediate roll; means for operating the intermediate roll; and means for driving the working rolls, each supporting roll having two trunnions at each end differing in diameter, the large trunnions being 70 mounted in the main bearings of the housings, and additional bearings outside of the main bearings for carrying the supporting rolls when driven by the working rolls, insuring the turning of the supporting roll 75 with the working roll.
10. The combination in a 5-high rolling mill, of housings; bearings in the housings; upper and lower working rolls adapted to 80 the bearings; a supporting roll back of each working roll and also adapted to the bearings in the housings; an intermediate roll; means for moving the intermediate roll; means for driving the working rolls, each 85 supporting roll having additional trunnions less in diameter than the main trunnions; bearings in which these trunnions are mounted; a cross beam carrying the upper bearings; means for supporting the beam; and 90 hydraulic cylinders having pistons supporting the bearings carrying the trunnions of the lower supporting roll.
11. The combination in a rolling mill, of a 95 working roll; a supporting roll located under the working roll, said working roll having two sets of trunnions, one greater in diameter than the other; main bearings for the large trunnions; supplemental bearings for the small trunnions; a pivoted cylinder; and a plunger mounted in each cylinder and 100 located under each supplemental bearing.
12. The combination of an upper working roll; an upper supporting roll; housings; bearings in the housings for the trunnions of the two rolls; a beam having depending bearings, the supporting roll having trunnions less in diameter than the diameter of the main trunnions and mounted in said latter bearings; cylinders carried by 105 the housings; plungers; a cross-head mount- 110 ed on the plungers; and rods connecting the cross-head with the beam carrying the upper supporting roll.
13. The combination in a rolling mill, of 115 housings; a lower working roll; a supporting roll therefor having trunnions; bearings in the housings for the trunnions; two cylinders, one adjacent each housing; and plungers in the cylinders for raising the supporting roll to allow it to be driven by the working roll.
14. The combination in a rolling mill, of 120 a housing; a lower working roll; a lower supporting roll mounted under the working roll and having trunnions; bearings in the 125 housings adapted to the trunnions, said supporting rolls having reduced trunnions and bearings therefor outside of the housings; pivoted cylinders mounted on the frame of the mill and having plungers; supporting 130 bearings for the reduced trunnions of the supporting roll; and means for centering said supporting roll.
15. The combination in a rolling mill, of 135 housings; bearings in the housings; a working roll and a supporting roll, the working roll having trunnions mounted in their respective bearings, the supporting rolls having reduced trunnions with bearings therefor outside of the housings, the bearings 140 having sockets; a plunger mounted under each of the last named housings and having a rounded projection adapted to the socket; a cylinder to which each plunger is adapted, each cylinder being pivoted to a fixed frame; and means for centering the supporting 145 rolls, the pivoted cylinders allowing for the slight movement.
16. The combination in a rolling mill, of 150 housings; a working roll and a supporting roll back of the working roll; bearings in the 155 housings for the two rolls, the supporting roll having additional trunnions less in diameter than the trunnions in the main bearings; bearings back of said reduced trunnions; a cylinder; a piston located under each of the last named housings for taking the weight off of the main bearings so as to insure the driving of the said supporting roll; a cross head attached to one supplemental bearing; spring mechanism acting upon the cross-head; a fixed frame in which the spring mechanism is mounted, said mechanism acting to return the roll to the central 160 position.
17. The combination in a rolling mill, of 165 housings; bearings therein; a roll having trunnions mounted in the bearings; a cross bar connected to said rolls; a frame through which the bar extends, said frame being 170 fixed; a spring on each side of the cross bar and located in the frame; plungers bearing against the cross bar and held in contact therewith by the springs so as to return the roll to its central position.

18. The combination in a rolling mill, of housings; bearings for the housings; a roll having trunnions mounted in the bearings; a cross-head attached to the roll; two sets of boxes; a spring in each box, the boxes being separated so as to allow the cross head to pass between them; plungers in the boxes; the springs forcing the plungers against the cross-head and acting to center the working roll in the housings.
19. The combination in a rolling mill, of housings; bearings in the housings; a roll having trunnions mounted in the bearings, said roll having extensions at one end; a disk secured to the extensions; a cage in which the disk is mounted; a cross head pivotally mounted on the cage; and springs on both sides of the cross-head acting to center the cross-head and the roll.
20. The combination of housings; bearings therein; a roll having trunnions mounted in the bearings; an extension on one end of the roll; a disk having hubs mounted on the extension; a cage in which the disk is free to rotate; washers located between the sides of the disk and the cage; an annular lining surrounding the disk within the cage; a cross-head pivotally mounted on the cage having arms; spring mechanism acting upon the arms and tending to keep the roll in the central position.
21. The combination in a rolling mill, of housings; main bearings in the housings; a working roll and a supporting roll having trunnions adapted to the bearings; the supporting roll having a coupling; a coupling block arranged to engage the coupling so that it will positively turn with it; a cap back of the coupling; a fixed frame; a spring in the fixed frame; a plunger within the frame forced against the cap by the said spring.
22. The combination in a rolling mill of housings; two longitudinal members spaced apart and extending from one housing to the other, boxes at the housings connecting the two longitudinal members, the several parts forming a cradle, and a roll mounted in the cradle and having its trunnions in the boxes.
23. The combination in a rolling mill, of housing, a cradle adapted to be removed through the housing, and a roll carried by the cradle and removable with it.
24. The combination in a rolling mill, of housings; a cradle consisting of two longitudinal members and two boxes, said boxes being mounted in the housings; a roll having trunnions mounted in the boxes, the two longitudinal members of the cradle acting as guides for the material as it passes between the rolls.
25. The combination of a rolling mill; housings; a cradle consisting of two longitudinal members; boxes; a roll mounted in the boxes; plates secured to the housings so that on the removal of the plates the cradle, with its roll, can be removed through the housings.
26. The combination in a rolling mill, of housings; a cradle consisting of two longitudinal members spaced apart and extending from one housing to the other and bearings forming the ends of the cradle and detachably connected to the longitudinal members—and a roll located in the cradle and having its trunnions mounted in the boxes.
27. The combination in a rolling mill, of housings; a cradle consisting of two longitudinal members; bearings located in the housings, the longitudinal members of the bearings having extensions projecting through the bearings; and means for securing the extensions to the bearings.
28. The combination in a rolling mill, of housings; a cradle consisting of two longitudinal members and bearings; bearings located in the housings, the longitudinal members having extensions projecting through the bearings; blocks extending through openings in the extensions, one of the blocks resting against the bearings.
29. The combination in a rolling mill, of housings; a cradle consisting of longitudinal members and bearings, said bearings being located in the housings; a roll mounted in the bearings, the longitudinal members forming channels; and means for supplying the channels with water.
30. The combination in a rolling mill, of housings; a cradle consisting of longitudinal members and bearings, said bearings being located in the housings; a roll mounted in the bearings, the longitudinal members forming channels; means for supplying the channels with water, the bottom of the channels being inclined toward the roll; and a loose board or plate in each channel bearing against the roll and tending to close the opening between the side members of the cradle and the roll so as to allow a body of water to remain in the channels.
31. The combination in a rolling mill, of housings; a cradle consisting of two longitudinal members and two bearings, said cradle being located in the housings; a roll mounted in the cradle and having trunnions adapted to the bearings, the longitudinal members acting as guides for the plate being rolled.
32. The combination in a rolling mill, of housings; two working rolls; an intermediate roll; means for driving the working rolls; a cradle for the intermediate roll; two rock shafts mounted in the housings, each rock shaft having an arm at each end; a cross bar at each end of the intermediate roll; links connecting the cross bar to the arms of the shaft; pivotal arms on the shafts; cylinders mounted in the overhead

structure of the housings; and a cross head to which the pistons of the cylinders are connected and links extending from the cross heads to the arms of the shafts so that 5 when the cylinders are operated the intermediate roll will be raised or lowered.

33. The combination in a rolling mill, of 10 housings; two working rolls; bearings mounted in the housings for said rolls; an intermediate roll; a cradle having bearings; 15 said cradle being mounted in the housings; two rock shafts adapted to the bearings in the housings; arms on the said rock shafts on the outside of the housings; a cross bar supporting each end of the cradle of the intermediate shaft; links connecting the 20 cross bars with the arms; intermediate arms on the shaft; three cylinders mounted in the overhead structure of the bearings; pistons in the cylinders; a cross head to

which the pistons are connected; and links connecting the cross head with the intermediate arms of the shafts.

34. The combination in a rolling mill of 25 upper and lower working rolls and upper and lower supporting rolls; a cradle for the upper working roll; hooked rods engaging the cradle; an overhead support for the hooks; and springs between the hooks and their supports. 30

35. The combination in a rolling mill of 35 housings; upper and lower working rolls and upper and lower supporting rolls; an overhead beam carrying the upper supporting roll; means for suspending said beam from the housings; a cradle carrying the upper working roll; and hooked rods engaging the cradle and connected to the overhead beam.

JOHN S. WORTH.
